UNITED STATES PATENT OFFICE.

WILLIAM P. MANUEL, OF LOS ANGELES, CALIFORNIA.

FEEDING DEVICE FOR PENCILS.

1,275,957.

Specification of Letters Patent. Patented Aug. 13, 1918.

Application filed January 3, 1918. Serial No. 210,202.

To all whom it may concern:

Be it known that I, WILLIAM P. MANUEL, a subject of the King of Roumania, residing at Los Angeles, in the county of Los Angeles and State of California, have invented new and useful Improvements in Feeding Devices for Pencils, of which the following is a specification.

This invention relates to means for feeding leads, erasers and the like, and pertains especially to lead pencils.

It is an object of this invention to provide a feeding device, by which a material to be used, such as an eraser or a lead, may be projected or retracted at will. Thus, in the case of a lead, it may be projected when it is desired to use it, and retracted when not in use. It also serves to feed more of the lead as the latter is worn away. In the case of an eraser, it may form part of an attachment to be applied to a pencil, and the eraser may be projected to compensate for wear.

I accomplish these objects by means of the embodiments of my invention illustrated in the accompanying drawings, in which;

Figure 1, is a perspective view of a pencil having an attachment secured thereto embodying a preferred form of my invention. Fig. 2 is an enlarged sectional view of the attachment shown in Fig. 1. Figs. 3 to 6 inclusive are elements of the attachment disassembled. Fig. 7 is a section as seen on a line 7—7 of Fig. 4 with the display sheets removed. Figs. 8 to 11 inclusive are elements of a modified form of my attachment shown assembled in Fig. 12. Fig. 13 is an elevation of a pencil having my invention embodied in the means for feeding the eraser and in the means for feeding the lead. Fig. 14 is a longitudinal section through the pencil shown in Fig. 13. Fig. 15 is an enlarged section as seen on the line 15—15 of Fig. 14. Fig. 16 is an enlarged fragment of Fig. 14. Fig. 17 is a section as seen on the line 17—17 of Fig. 14. Fig. 18 is an elevation of the eraser carrier. Fig. 19 is a section as seen on the line 19—19 of Fig. 14. Fig. 20 is an elevation of an attachment such as is shown in Figs. 13 to 18 inclusive, but having a sleeve adapted to slip over and grip a pencil by friction.

Referring particularly to Figs. 1 to 7 inclusive, which show the preferred form of my invention, I have shown an attachment embodying my invention secured to a pencil

—P—. The pencil —P— may be of the type shown in Figs. 13 and 14. However, any other suitable type of pencil may be used. The pencil shown is, however, of the type in which independent leads are fed from a casing.

The attachment is comprised of a connector —A—, a display barrel or holder —B—, a shell —C—, an eraser carrier —D—, and a cap —E—.

The connector —A— is of bell shape having an internal thread at its small end adapted to engage with a similar thread on the end of pencil —P—. A partition wall 70 21 divides the bell mouth from the portion which connects to the pencil. The large end of the bell is internally threaded.

The barrel —B— is of tubular form and has an upper flange 22 and a lower flange 23. Longitudinal flanges 24 and 25 connect end flanges 22 and 23 and form a groove 26. Diametrically opposite to groove 26 is a rib 27, which is rabbeted at the sides, forming with the flanges recesses on the face of the barrel for receiving display sheets. A neck 28 is formed on the barrel. On neck 28 is a pin 29. Formed in the bore of the barrel is a slot 30 adapted to receive a projection on the eraser holder.

The shell —C— comprises a lower ring 31 externally threaded. Posts 32 and 33 connect ring 31 with an upper ring 34, the latter being of angular section as shown in Fig. 2. On the inner surface of post 32 and ring 31 is a rib 35 adapted to be disposed in slot 26 of the display barrel. Rotatably secured on ring 34 is an apron 36, which is fixed to a feeder sleeve 37 and preferably formed integral therewith. Feeder sleeve 37 is formed with an internal thread. In order to secure the feeder to the shell a ring 38 is secured to the feeder sleeve. The feeder sleeve may be rotated with respect to the shell by grasping the apron 36 and turning the same.

The eraser carrier —D— is tubular in form and has an external thread 39 adapted to engage with the internal thread in the feeder sleeve. A ring 40 is formed on the carrier at the lower edge to provide a shoulder for abutting the feeder sleeve and to limit its movement. Upon the ring 40 is a tongue 41 adapted to ride in the slot 30. Erasers 42 and 43 are disposed in the bore of the carrier. Eraser 42 is for use, while eraser 43 is a reverse eraser.

The attachment is assembled in the following manner; calenders or display sheets 44 and 45 are placed in the recesses on the face of barrel —B— and the barrel —B— 5 is slipped into shell —C— with the rib 35 in the slot 26, thereby holding the barrel and shell in registration. The feeder sleeve 37 fits loosely within the bore of the barrel and may be rotated by turning the apron 36. 10 The eraser carrier —D— is then slipped into the barrel —B— with the tongue 41 disposed in slot 30. This prevents rotation of the carrier, but permits longitudinal movement with respect to the barrel and sleeve. Sleeve 15 37 is then rotated so that the thread on the interior engages the thread 39 on the carrier. Cap —E— which has a bayonet slot 44 is slipped upon the neck 28 of the barrel with the pin 29 in slot 44 and locked in position. The shell is now screwed to connector 20 —A— as shown in Fig. 2. The entire attachment may then be screwed on to the end of the pencil —P—.

It is obvious that the eraser 42 may be 25 projected or retracted at will. When the eraser is worn down so that it is no longer serviceable, the attachment may be disassembled and the reserve eraser 43 placed in the position of eraser 42.

30 In Figs. 8 to 12 inclusive a modified form of the device adapted to fit on the end of a pencil and provided with an adjustable eraser, is shown. The assembled device disposed on the end of a pencil is shown in 35 Fig. 12.

The device comprises a pencil gripping sleeve —a—, a display barrel —b—, a shell —c— and an eraser carrier —d—. The elements —a—, —b—, and —c— are similar 40 to the elements —A—, —B—, and —C— of the preferred form of device. The sleeve —a— is slit to provide spring fingers and has a retaining member 45 fixed thereto. At its upper portion the sleeve is expanded as indicated by 46 and provided with an internal 45 thread at the expanded portion.

The barrel —b— is provided with recessed faces for the reception of display sheets, as described for the holder of the preferred 50 form, and is also provided with a groove 47. On its inner face, it is provided with a longitudinal groove 48.

The shell —c— has a lower ring 49 externally threaded and posts 50 and 51 connecting with an upper ring 52. The upper ring 52 is reduced in diameter and rotatably mounted thereon is the apron portion 53 of a feeder sleeve 54. Sleeve 54 is of such diameter that it will loosely fit within the bore of 60 barrel —b— and has an internal thread. The rotatable connection of the feeder to the shell is like that shown in Fig. 2.

The carrier —d— for the eraser is tubular in form and is provided with a thread 55 65 upon its exterior. The lower part of the

carrier is expanded to form an abutting shoulder 56, and extending from said shoulder is a tongue 57 adapted to engage the slot 48. Erasers 58 and 59 may be slipped into the tubular bore. 70

The device is assembled in the following manner: The display barrel —b— is telescoped within the shell —c—, the tongue 60 and slot 47 coöperating to hold the holder and sleeve in proper position, the feeder 75 54 being within the bore of the barrel —b—. The eraser carrier is now placed within the display barrel, the tongue 57 riding in groove 48, thereby preventing rotation of the carrier with respect to the display barrel, but 80 permitting longitudinal movement of the carrier. The feeder 54 is now rotated by grasping the apron 53 and turning the same, thereby engaging the thread on the interior of sleeve 54 with the thread 55 on the eraser 85 carrier. It is evident that the eraser 58 may be projected or retracted by rotating the feeder. The assembled shell, display barrel, and eraser carrier are now secured to the pencil sleeve —a—, the thread on ring 49 90 being engaged with the thread on the interior of ring 46. In this assembled condition the attachment may be placed on the end of the pencil as indicated in Fig. 12.

It will be noticed that the eraser carrier 95 has an additional eraser 59. This is merely a reserve eraser which may be substituted for the eraser 58 when the latter is worn.

Referring particularly to Figs. 13 to 20 inclusive, a pencil for feeding leads and an 100 eraser feeding attachment without display means is shown. The eraser feeding mechanism will be first described.

A cylindrical shell 61 has rotatably mounted within it a tube or sleeve 62. The 105 sleeve 62 is expanded at its upper end to form a bead 63, which overhangs the upper edge of shell 61. Sleeve 62 is provided with an internal thread 64. Secured to shell 61 at the lower portion thereof is a sleeve 65, 110 which has slots formed longitudinally at diametrically opposite points providing two sections. A complete ring 66 is formed at the upper part of the sleeve and is flanged to overhang bead 63, thereby holding the rotatable sleeve in place. The eraser carrier is of tubular form as shown in Fig. 18 and has upon diametrically opposite portions of its surface, sections of mutilated thread 68 and 69. The mutilated sections of thread fit 115 within the slots formed in sleeve 65, thereby permitting longitudinal movement of the holder but preventing rotation. Erasers 70 and 71 are placed in the bore of the holder 120 67, eraser 70 being for use and 71 as a reserve eraser. The thread sections 68 and 69 mesh with the thread 64 on sleeve 62, so that upon rotating sleeve 62, the carrier 67 is projected or retracted. Sleeve 65 is internally threaded at its lower end and adapted 125 130

to engage with external threads on connector 72. Connector 72 is internally threaded and forms a cap for the end of the pencil.

It is obvious that the eraser may be fed 5 by turning the ring 63. When eraser 70 is no longer useful because of wear, the eraser 71 is substituted therefor. This change may be accomplished in the following manner: The connector 72 is detached from the 10 attachment and the eraser carrier removed from the shell. This may be done by turning the ring 63 in the direction to retract the carrier.

The construction shown in Fig. 20 differs 15 from that last described only in the connector 63 which takes the place of connector 72. Connector 73 is suitable for slipping onto the end of an ordinary wooden lead pencil and is provided with a retainer 74.

20 Referring particularly to Figs. 18, 14 and 17 the casing for the pencil is indicated by 75 and is preferably of metal. A tapered end 76 is attached thereto by means of a thread on its interior, which engages with 25 a thread on the exterior of the lower end of the casing. A rotatable tip 77 is secured to the end 76, and is provided with a bore in which a lead is adapted to snugly fit. Secured to the tip 77 is a sleeve 78, which is 30 provided at its upper end with an internal thread. A shoulder 79 is formed on the sleeve 78 to secure the latter to the end 76. A carrier 80 for the lead has a thread 81 adjacent its lower end adapted to engage with 35 the thread on the interior of sleeve 78. Formed on the end of carrier 80 is a ball 82. A clutch 83 for the lead has a socket in which the ball 82 is disposed, thereby forming a ball and socket joint connection between the 40 clutch and the carrier. This permits movement of the lead 84 out of alignment with carrier 80 and thereby prevents breakage, which so often occurs in pencils of this type when the lead is forced through the tip. On 45 the upper end of carrier 80 is a wing 85.

Disposed in the upper end of casing 75 is a magazine member 86 for lead. The magazine comprises a ring with fins 87 radiating therefrom, and forming storage pockets, 50 each one of which will hold one lead. A pocket 88 to slidably receive the fin 85 is formed in the magazine. The disposition of the wing 85 in the pocket 88 prevents rotation of the carrier 80, but permits longitudinal movement.

Each of the pockets for lead may be filled 55 with a lead, the cap formed by the connector 72 holding the same in place. This is a very convenient arrangement, as new leads are 60 available for use, and it may be seen at a glance how many leads are left in the magazine.

The lead for use may be advanced or retracted by turning the tip 77 of the pencil.

65 The thread on sleeve 78 engaging the thread

81 on the carrier compels longitudinal movement on the carrier and with it the lead, the wing 85 and pocket 88 preventing rotation. The connector or cap 72 serves to limit the movement of carrier 80 as the 70 lead is retracted in the casing.

What I claim is:

1. A pencil attachment comprising a shell having a display opening, and a holder for detachably carrying sheets on its face 75 removably mounted within said shell so as to display said sheets.

2. A pencil attachment comprising a shell having a display opening, a holder for detachably carrying sheets on its face removably mounted within said shell so as to display said sheets, and means to detachably mount said attachment on said pencil. 80

3. A pencil attachment comprising a shell having a display opening, and a barrel 85 for detachably holding sheets on its face telescopically mounted within said shell so as to display said sheets.

4. A pencil attachment comprising a shell having a display opening, a barrel for 90 detachably holding sheets on its face telescopically mounted within said shell so as to display said sheets, and pencil gripping means to detachably secure said attachment on a pencil. 95

5. A pencil attachment comprising a shell having a display opening, and a barrel for detachably holding sheets on its face telescopically mounted within said shell so as to display said sheets, said shell and barrel 100 provided with means to prevent their relative rotation.

6. A pencil attachment comprising a shell having a display opening, a barrel for 105 detachably holding sheets on its face telescopically mounted within said shell so as to display said sheets, said shell and barrel provided with means to prevent their relative rotation, and means to detachably mount said attachment on a pencil. 110

7. A feeding device for pencils comprising a shell, a sleeve rotatably secured thereto, said sleeve having a thread, a carrier mounted therein having a thread engaging the thread on said sleeve, and means adapted 115 to visibly carry display matter removable from said shell for holding said carrier against rotation with respect to said shell but permitting longitudinal movement.

8. A feeding device for pencils comprising a shell, a sleeve rotatably secured thereto having an internal thread thereon a carrier having an external thread engaging the thread on said sleeve, and means adapted to visibly carry display matter removable from 120 said shell for holding said carrier against rotation with respect to said shell but permitting longitudinal movement thereof.

9. A feeding device for pencils comprising a shell, a sleeve rotatably secured with- 125

in said shell, said sleeve having a thread, a carrier mounted therein having a thread engaging the thread on said sleeve, and means adapted to visibly carry display matter removable from said shell for holding said carrier against rotation with respect to said shell but permitting longitudinal movement thereof.

10. A feeding device for pencils comprising a shell, a sleeve rotatably secured within said shell, having an internal thread

thereon, a carrier having an external thread engaging the thread on said sleeve, and means adapted to visibly carry display matter removable from said shell for holding 15 said carrier against rotation with respect to said shell but permitting longitudinal movement.

In witness that I claim the foregoing, I have hereunto subscribed my name, this 28th 20 day of December, 1917.

WILLIAM P. MANUEL.
